(57) **CLAIM**

The ornamental design for a computer display filter, as shown and described.

DESCRIPTION

FIG. 1 is a front view of a computer display filter; FIG. 2 is a rear view of the computer display filter in FIG. 1; FIG. 3 is a left-side view of the computer display filter in FIG. 1; FIG. 4 is a right-side view of the computer display filter in FIG. 1; FIG. 5 is a top view of the computer display filter in FIG. 1; FIG. 6 is a bottom view of the computer display filter shown in FIG. 1; FIG. 7 is a front, top and right side perspective view of the computer display filter shown in FIG. 1; and, FIG. 8 is another front, top and right side perspective view of the computer display filter shown in FIG. 1 shown in an environment of use. The broken lines shown in FIG. 8 illustrate the environment of the claimed design and form no part thereof.

1 Claim, 8 Drawing Sheets
